FRONT FOR RADIOCABINETS

John L. Finnegan, Nashville, Tenn.

Application March 14, 1932, Serial No. 598,828

4 Claims. (Cl. 312—7)

My invention relates to radio cabinets and particularly to the fronts thereof, and the object of the invention is to provide a device of this character which is simple of construction, 5 reliable and efficient in action, and which may be manufactured and sold at a comparatively low cost.

The invention consists of the features of construction, combination and arrangement of 10 parts, hereinafter fully described and claimed, reference being had to the accompanying drawing, in which:

Figure 1 is a perspective view of a radio cabinet with the front attached thereto.

15 Figure 2 is a vertical sectional view of the device.

Figure 3 is a perspective view of the metal support.

20 Figure 4 is a perspective view of one of the colored cards.

I have provided a frame front 10 which is adapted to receive the ground glass plate 11 and is hinged at 12 and fastened to the cabinet front by means of any snap fastener 13.

25 The ground glass plate 11 extends up the front part of the frame and is adapted to receive the grill-work 14.

The glass plate 11 is transparent at 15, so that the dial of the radio set, or other instrument 30 or device, can be read therethrough and the portion 16 is provided with a ground surface to receive pencil notations etc. which may be easily removed with a damp cloth.

A metal support 17 is attached to the glass 35 plate by means of the screws 18 which extend through the front of the glass and are curved to form a hook 19 to which are suspended articles 20 such as a radio log, timepiece, pencils, etc.

The metal support 17 is provided with a cut- 40 out portion 21 which is directly in front of a radio set 27 which enables the dial readings to be seen through the transparent portion 15 of the glass front.

The openings 23 in the glass front are so 45 located as to allow the knobs 29 of the radio set 27 to extend therethrough and be operated from the front.

The light from the dial of the radio set serves 50 to illuminate the entire front, but if additional illumination is required, light bulbs 30 may be arranged on the bottom support 31 and connected to an outside lighting connection, not shown in the drawing. Extending at right angles to the back of the support 17 is a flange 22 having a recess 23 and is adapted to receive and

support the colored cards 24. The card 25 may be inserted between the glass 11 and the support 17 by means of the slot 26 in the support 17.

By means of this apparatus it is possible to illuminate the glass front of the radio cabinet, either by the light from the dial or by separate lighting means. The insertion of various colored cards provides means for giving a colored ornamental effect or colored lights may be used with or without the colored cards.

The construction and operation of the device will be readily understood from the foregoing description, and it will be seen that the invention provides a simple, reliable and efficient type of device of this character.

Having thus fully described my invention, I claim:

1. In a device of the character described, the combination of a radio front panel provided with operating means for a radio cabinet, said front conforming substantially to the configuration of said cabinet and pivoted thereto and including transparent portions, a frame secured to the inner side of said radio front panel and disposed above said operating means, said frame including a portion conforming substantially to the configuration of said front member, a channel member extending across said frame and adapted to support a translucent member adjacent a portion of said panel, said frame having a slotted portion whereby said translucent member may be removably applied to said frame.

2. In a device of the character described, the combination of a radio cabinet having a control panel provided with operating means for the radio provided in said cabinet, said panel conforming substantially to the configuration of said cabinet and pivoted thereto, said front member including a transparent member having a portion consisting of a ground surface, a frame secured to the inner side of said front member and disposed above said operating means.

3. In a device of the character described, the combination of a radio cabinet having a transparent front member provided with operating means for the radio provided in said cabinet, said transparent front member conforming substantially to the configuration of said cabinet and pivoted thereto, a frame member secured to the inner side of said transparent front member and disposed above said operating means, said frame member including a portion conforming substantially to the configuration of said front transparent member and having a

securing portion for fastening said frame to said front member, a channel member extending across said frame member and adapted to support a translucent member adjacent a portion of said panel, said frame having a slotted portion whereby the said translucent member may be removably applied to said frame, means for illuminating said transparent front member, said means consisting of lights disposed substantially to the rear of said frame.

4. In a device of the character described, the combination of a radio cabinet having a transparent front member provided with operating means for the radio provided in said cabinet, said front member conforming substantially to

the configuration of said cabinet and pivoted thereto and including transparent portions, a frame secured to the inner side of said front member and disposed above said operating means, said frame member including a substantially U-shaped portion and conforming substantially to the configuration of said front member, one side of said U-shaped member being slotted whereby a translucent member may be removably applied to said frame, a channel member extending across said U-shaped portion, a large opening in the rear of said U-shaped member of slightly less area than said U-shaped member.

JOHN L. FINNEGAN.
